[57] CLAIM

The ornamental design for a pajama ensemble for use with an intravenous apparatus, as shown and described.

DESCRIPTION

FIG. 1 is a perspective view of a pajama ensemble for use with an intravenous apparatus showing our new design;

FIG. 2 is an enlarged perspective view of the top element of the pajama ensemble;

FIG. 3 is a perspective view of FIG. 3 showing the sleeves in an open position;

FIG. 4 is a front elevational view of FIG. 2;

FIG. 5 is a rear elevational view of FIG. 2;

FIG. 6 is a right side elevational view of FIG. 2;

FIG. 7 is a left side elevational view of FIG. 2;

FIG. 8 is a top plan view of FIG. 2;

FIG. 9 is a bottom plan view of FIG. 2;

FIG. 10 is an enlarged perspective view of the trouser element of the design shown in FIG. 1;

FIG. 11 is a perspective view of FIG. 10 shown in an open position;

FIG. 12 is a front elevational view of FIG. 10;

FIG. 13 is a rear elevational view of FIG. 10;

FIG. 14 is a right side elevational view of FIG. 10;

FIG. 15 is a left side elevational view of FIG. 10;

FIG. 16 is a top plan view of FIG. 10; and,

FIG. 17 is a bottom plan view of FIG. 10.
